UNITED STATES PATENT OFFICE.

WILLIAM E. BARTMESS, OF KENWOOD, OKLAHOMA.

LOCK.

Application filed October 7, 1926. Serial No. 140,170.

This invention relates to locks, and has more particular reference to a padlock of generally simplified and improved construction.

- 5 The primary object of the present invention is to provide a padlock wherein simple and effective means is provided for releasably securing or retaining the shackle of the lock in locking position.
- 10 A more specific object of the invention is to provide an improved form of padlock including a pivoted shackle, and simple and effective means for releasably retaining the bow or shackle in locked position including
- 15 manually rotatable tumbler disks capable of being set for permitting movement of the bow or shackle to unlocked or open position.

- Another object of the invention is to provide a padlock of the above type which is 20 susceptible of slight structural changes to vary the operating combination, to prevent duplication of the locks.

- 25 A further object of the invention is to provide a padlock of the above kind wherein simple means is provided for facilitating manual rotation and setting of the tumbler disks for effecting release of the bow or shackle in an expeditious manner by an authorized person, while at the same time 30 presenting a construction wherein it will be extremely difficult for an unauthorized person to effect release of the bow or shackle.

- Other objects will become apparent as the 35 nature of the invention is better understood, and the same consists in the novel form, combination and arrangement of parts herein-after more fully described, shown in the accompanying drawings and claimed.

- In the drawings, wherein like reference 40 characters indicate corresponding parts throughout the several views,

Figure 1 is a side elevational view of a 45 padlock constructed in accordance with the present invention, with the bow or shackle in locked position,

Figure 2 is a view of the padlock shown 50 in Figure 1 with one of the sections of the padlock casing removed and pivots and fastening elements in section, the tumbler disks being shown in locking position;

Figure 3 is an edge elevational view looking 55 toward the left of Figure 1,

Figure 4 is a perspective view of one of the tumbler disks;

55 Figure 5 is an enlarged fragmentary perspective view showing an end portion of an

arm which is operatively connected to the bow or shackle and operatively associated with the tumbler disks for releasably retaining the bow or shackle in locked position. 60

Figure 6 is a view similar to Figure 2 with the tumbler disks shifted to releasing position and the bow or shackle in its released position,

Figure 7 is a central sectional view taken 65 substantially upon line 7—7 of Figure 1,

Figure 8 is a sectional view taken upon line 8—8 of Figure 1,

Figure 9 is an inside elevational view 70 of one of the sections of the lock casing,

Figure 10 is a perspective of a device 75 which may be provided for association with the casing of the padlock to facilitate setting of the tumbler disks for the release of the bow or shackle, and

Figure 11 is an elevational view illustrating 80 the manner in which the device of Figure 10 is applied to the padlock when used for facilitating unlocking of the shackle, the padlock being illustrated on a reduced scale by dotted lines to correspond with the reduced scale upon which the device of Figure 10 is shown in this figure.

Referring more in detail to the drawings, the embodiment of the invention illustrated 85 consists in a padlock having a casing composed of a pair of somewhat similar sections 5 and 6 rigidly and permanently secured together in side by side contiguous relation by suitable means such as rivets 7 90 passing through the casing sections at suitable spaced points near the edges of the casing sections. The sections 5 and 6 of the lock casing are provided in their adjacent sides or surfaces with mating relatively 95 large and circular recesses 8 which cooperate to form a circular chamber in the lock casing within which are rotatably fitted a plurality of tumbler disks 9. As shown, a pair of the disks 9 is provided in the recess of each 100 casing section, and one pair of tumbler disks is spaced from the other pair as shown in Figure 7, for a purpose which will presently become apparent. The tumbler disks 9 are preferably rotatable about a fixed axial pivot in the form of a rivet 10 which also aids in retaining the casing sections together. Rigid with and projecting outwardly from the edge of each tumbler disk 9 is an arm 11 terminating in a lateral outer 110 or free end portion 12 which is tapered so as to form a pointer. As shown, the arms

11 of one pair of tumbler disks 9 are arranged to freely move within an elongated arcuate slot which opens through one side of one section of the lock casing, while the 5 arms 11 of the other pair of tumbler disks are movable in an elongated arcuate slot in the opposite side of the other section of the lock casing. The slot at one side edge of the lock casing is formed by recessing one 10 of the casing sections near one side as indicated at 13 in Figure 8 and 9, while the other slot of the lock casing is formed by similarly recessing the other casing sectioned at the opposite side of the latter as 15 indicated at 14. As clearly shown in the several views, the side edge portions of the lock casing coincident with the slots through which the arms 11 project are of arcuate form and concentric with the pivot 10 of 20 the tumbler disk, and the lateral outer ends of the arms 11 are arranged to move beside these arcuate edges which are suitably graduated as indicated at 15. Thus, when the casing sections are assembled, the sides of 25 the lock will be formed to provide slots through which the arms of the tumbler disks may be actuated, while the lower side of the lock casing will be closed, for a purpose which will later appear. Referring 30 to Figure 3 it will be seen that graduations are provided at each edge or along each longitudinal edge of each slot through which the arms 11 project, and the lateral ends of adjacent pairs of arms 11 are directed 35 in opposite directions so as to respectively cooperate with the graduations at opposite sides of the slots.

Each tumbler disk 9 is provided with a radial or substantially radial slot 16 which 40 opens through the periphery of the tumbler disk, and these slots 16 are so located with relation to the arms 11, that the arms 11 of one pair of disks must be set in different positions at one side of the lock casing, and 45 the arms 11 of the other pair of disks must be set at different positions at the other side of the lock casing in order to bring the slots 16 of all of the tumbler disks into alignment or registration beneath the pivot 10. As 50 previously noted, the lower closed portion of the lock will prevent unauthorized persons observing the position of the radial slots in the disks which would enable them to adjust the disks to effect release of the shackle.

55 A bow or shackle 17 is pivoted at one end upon one of the upper rivets 7 adjacent one side edge of the lock casing so as to be capable of swinging movement from closed to open position and vice versa, the casing 60 having a socket in the upper end thereof adapted for reception of the other or free end of the bow or shackle when the latter is in locked or closed position. This socket is formed by the provision of a pair of mating recesses 18 in the adjacent faces of the cas-

ing sections, and the pivoted end of the bow or shackle is disposed in a recess provided in the inner face of one of the casing sections as indicated at 19 in Figure 2, whereby such end of the bow or shackle is free to be swung 70 and positioned between the casing sections.

Rigid with and projecting inwardly from the pivoted end of the bow or shackle 17 is an arm 20 which extends into the space between the pairs of tumbler disks and terminates at its inner end at a point above the pivot pin of the tumbler disks. A detent arm 21 is also disposed between the pairs of tumbler disks and is pivotally attached at its upper end to the inner end of the arm 20 75 as indicated at 22, said detent arm 21 being of a length to extend past the pivot pin to the lower edges of the tumbler disks where it is provided at its lower free end with a transverse head 23. The head 23 is rigid 80 with the detent arm 21 and is positioned in engagement with the edges of the tumbler disks at the lower side of the lock casing when the shackle 17 is in closed or locked position, the head 23 being of such length as 85 to extend beyond opposite sides of the detent arm and entirely across the edges of all of the tumbler disks as clearly shown in Figure 7. It is thus evident that when the parts are disposed as shown in Figure 2 with the tumbler disks 9 variously positioned with their slots 16 out of registry, the head 23 by engagement with the disks, will prevent upward movement of the arm 20 and will accordingly retain the bow or shackle 17 in 90 closed position, at which time the padlock is in a locked condition.

However, by properly setting the pointers 12 of the respective arms 11 of the tumbler disks with relation to the graduations 15 on 105 the lock casing, the tumbler disks 9 will be partially rotated until brought to a position wherein the slots 16 of all the tumbler disks are registered beneath the pivot pin and coincident with the head 23 of the detent arm 110 21. Obviously, when the tumbler disks are thus positioned with all of the slots 16 registered, the head 23 will be free to move upwardly in the slots 16 toward the pivot pin, thereby permitting the arms 20 and 21 to 115 rise and allowing the bow or shackle 17 to be swung to the open position indicated in Figure 6. Naturally, one familiar with the proper setting of the pointers 12 may readily set the tumbler disks for effecting release of 120 the shackle, while one not familiar with the same will have considerable difficulty in doing so.

As disclosed in Figures 10 and 11, in lieu of the use of the graduations 15, a device 125 may be provided for application to the lock casing for facilitating proper positioning of the pointers 12 wherein the tumbler disks are set with their slots 16 registered to permit opening or unlocking of the bow or 130

shackle 17. This device preferably consists of a flat plate 24 adapted to be flatly disposed against one side of the lock casing and having a pair of laterally extending lugs 25 up-
6 on each end thereof disposed to extend across the respective slots in which the tumbler disk arms 11 are movable and so spaced that when the arms 11 are set with one of the same contacting the inner edge of each of
10 the lugs 25, the discs 9 will be positioned with their slots 16 registered as shown in Figure 6. The plate 24 is preferably provided with curved end flanges 26 adapted to snugly engage the arcuate side edge portions
15 of the lock casing when applied, as shown in Figure 11, whereby the device is firmly retained properly positioned, except for the requirement of manually holding the plate 24 into contact with the surface of the lock
20 casing. The lugs 25 preferably project from the ends of the flanges 26 as shown, and in order to permit the plate 24 to flatly engage the lock casing, the same is provided with a central opening as at 27, into which the adja-
25 cent head of the rivet or pivot pin 10 may project. Obviously, the distance at which the lugs 25 of each pair are spaced apart will be entirely governed by the relation of the arms 11 to the slots 16 of the tumbler disks
30 and the corresponding relative positions at which the arms 11 must be set for effecting registering of the slots 16 of the tumbler disks. Obviously, the device of Figure 10
35 may be quickly applied to the padlock as indicated in Figure 11 and the pointers can be quickly set so that the unlocking of the shackle may be effected in an expeditious manner. It is simply necessary to know which pointers are to engage with the up-
40 permost lugs, and as shown, the inner disk of each pair is the one the arm of which is to be swung upwardly to engage the uppermost lug 25 at each side of the lock casing.

In the embodiment of the invention illus-
45 trated, it will be readily apparent that the radial slots 16 in the tumbler disks may be formed in a variety of positions with respect to the arms 11 of the disks. It is contemplated to prevent duplication, of the un-
50 locking combination to vary the position of the radial slot of at least one tumbler disk, so that a great number of combinations may be produced. As an example, it will be noted that the slot in each disk of the series
55 may be so formed as to be positioned at many different angles, and as there are four distinct disks the number of combinations which locks of this type may possess will be sufficient to prevent duplication. Fur-
60 thermore, it is contemplated to produce pad-locks of this general structural form embodying from two to six or more tumbler disks. The cheaper locks employing only two disks would not be susceptible of as
65 great a range of relative arrangement of

the slots therein as would locks having a greater number of disks, but would nevertheless be susceptible of varied combinations. The number of combinations might also be increased by increasing the diameters of the 70 disks, it being readily apparent that disks of larger diameter would permit the formation of a greater number of slots so as to present a relatively greater number of different combinations. 75

From the foregoing description it is believed that the construction and operation as well as the advantages of the present invention will be readily understood and appreciated by those skilled in the art. 80

Minor changes may be made without departing from the spirit and scope of the invention as claimed.

What I claim as new is:—

1. A lock comprising a casing including assembled relatively fixed sections, a shackle carried by the casing and movable to locking and released positions, a plurality of slotted disks arranged in the casing and rotatable to relative positions with their slots in registry at a predetermined point and to other relative position with their slots out of registry, manually operable means for adjusting said tumbler disks, and a member operatively pivotally connected to an angular extension of the shackle and extending substantially diametrically of the disks and restrained from movement by the tumbler disks when the latter are relatively positioned with their slots out of registry for 90 restraining the shackle in locked position, said member being movable into the slots of the tumbler disks when the latter are positioned with their slots in registry for permitting movement of the shackle to released position, said casing having circumferential slots in its periphery, and said manually operable means embodying arms rigid with the tumbler disks and projecting outwardly 95 through and movable in said slots. 100

2. A lock comprising a casing including assembled relatively fixed sections, a shackle carried by the casing and movable to locking and released positions, a plurality of slotted tumbler disks arranged in the casing and rotatable to relative positions with their slots in registry at a predetermined point and to other relative positions with their slots out of registry, manually operable means for adjusting said tumbler disks, a 110 detent member pivotally connected with an angular extension of the shackle and restrained from movement by the tumbler disks when the latter are relatively positioned with their slots out of registry for restraining the shackle in locking position, said detent member being movable into the slots of the tumbler disks when the latter are positioned with their slots in registry for permitting 115 movement of the shackle to released position, 120

125

4. said casing having circumferential slots in its periphery, said manually operable means embodying arms rigid with the tumbler disks and projecting outwardly through and movable in said slots, and means applicable to the casing and having elements in the path of movement of said arms for facilitating proper setting of the tumbler disks for release of the locking elements.
5. A lock comprising a casing including assembled relatively fixed sections, a shackle carried by the casing and movable to locking and released position, a plurality of slotted tumbler disks arranged in the casing and rotatable to relative positions with their slots in registry at a predetermined point and to other relative positions with their slots out of registry, manually operable means for adjusting said tumbler disks, a detent member pivotally connected with an angular extension of the shackle and restrained from movement by the tumbler disks when the latter are relatively positioned with their slots out of registry for restraining the shackle in locking position, said member having a head engageable and movable in the slots of the tumbler disks when the latter are positioned with their slots in registry for permitting movement of the shackle to released position, said casing having circumferential slots in its periphery, said manually operable means embodying arms rigid with the tumbler disks and projecting outwardly through and movable in said slots, and means for determining the adjustment of said arms to bring the disks into position with their slots in registration, said last named means comprising a plate removably applicable to the casing and having lateral lugs arranged to constitute stops for the arms of the tumbler disks.
6. A padlock including a casing, a shackle carried by the casing and movable to locking and released positions, a plurality of slotted tumbler disks rotatably mounted in the casing and adjustable to relative positions with their slots out of registry and to other relative positions with their slots in registry at a predetermined point, and a member connected to the shackle and provided with a head engageable with the peripheries of the disks and restrained from movement by the disks when any one of the latter is positioned with its slot removed from such predetermined point for securing the shackle in locking position, said head being movable into the slots of the tumbler disks when all of the latter are positioned with their slots in registry for permitting movement of the shackle to released position, said casing having elongated slots in the side edges thereof, and arms rigid with the tumbler disks and projecting outwardly through said slots of the casing for being manually operated to set the tumbler disks.
7. A padlock including a casing, a shackle having one leg pivoted in the casing and movable to locking and released positions, a plurality of slotted tumbler disks rotatably mounted in the casing and movable to relative positions with their slots out of registry and to other relative positions with their slots in registry at a predetermined point, the said leg of the shackle having an angular extension within the casing, and a member connected to the said arm and having a transverse head engageable with the peripheries of the disks and restrained from movement by such engagement when any one of the disks is positioned with its slot removed from such predetermined point for restraining the shackle in locking position, said head being movable into the slots of the tumbler disks when all of the latter are positioned with their slots in registry for permitting movement of the shackle to released position, said casing having circumferential slots in the periphery thereof, and arms rigid with the tumbler disks and projecting outwardly through said slots and manually adjustable to adjust the tumbler disks, the periphery of the casing at the opposite sides thereof being curved concentric with the axis of rotation of the tumbler disks and having graduations along the sides of said slots, and lateral pointers on the outer ends of said arms of the tumbler disks movable along the side portions of the casing and past said graduations.
- In testimony whereof I affix my signature.
- WILLIAM E. BARTMESS.
